CLAIM

The ornamental design for a contoured pillow, as shown and described.

DESCRIPTION

FIG. 1 is a top perspective view of a contoured pillow; FIG. 2 is a top plan view of the contoured pillow; FIG. 3 is a bottom plan view of the contoured pillow; FIG. 4 is a front elevation view of the contoured pillow; FIG. 5 is a rear elevation view of the contoured pillow; FIG. 6 is a right side view of the contoured pillow; and, FIG. 7 is a left side view of the contoured pillow.

The contoured pillow is used to support the head of a person. The broken lines which show the H-shape in FIGS. 1, 2, and 3, represent stitching and are part of the claimed invention.

1 Claim, 4 Drawing Sheets(56)
